APPARATUS FOR REMOVING LIQUIDS FROM PERFORATED ROTATING SHELLS

John E. Goodwillie and Lloyd Hornbostel, Beloit, Wis., assignors to Beloit Iron Works, Beloit, Wis., a corporation of Wisconsin

Application May 13, 1949, Serial No. 93,144

5 Claims. (Cl. 92—53)

1

The present invention relates to apparatus for removing liquids from perforated rotating shells, and more particularly to apparatus for removing liquids from the surface perforations of a rotatable suction shell or drum employed in a paper making machine.

The employment of suction rolls or drums in paper making machines to remove water from the wet paper web has long been known in the art. Such suction drums are typically provided with means for receiving water removed from the web and for conveying this water from the interior of the shell. However, fully satisfactory means has not heretofore been provided for removing water from the relatively small diameter perforations or holes in the shells of such drums. It has been found that, in certain applications, particularly in those machines which operate at low web speeds, the centrifugal force generated upon rotation of the shell is insufficient to throw water outwardly from the holes or perforations of the shell. Accordingly, moisture or water in these perforations will not be effectively removed, and this moisture may later contact the web to interfere with the drying efficiency of the drum.

The present invention now provides novel and inexpensive means for effectively removing liquids from the surface perforations of rotatable perforated shells or suction drums. In general, the present invention includes means for introducing gaseous fluid under pressure into the interior of the rotating drum or shell with the escape of this fluid through the surface perforations of the drum carrying with it any liquid contained therein. Means are also provided for catching the liquid thus escaping from the drum and for conveying the liquid from the machine without the possibility of wetting the paper web.

The means of the present invention may be used in connection with a suction drum or roll at any place where such a drum may be employed in a paper making machine. For example, the present invention may be employed in connection with a suction drum press assembly or with a suction roll positioned in the drier press assembly of the machine. Alternatively, the device of the present invention may be employed in connection with suction rolls positioned in other portions of the machine, as with a suction couch roll.

A feature of this invention is its adaptability to standard suction roll constructions so that it can be added to the conventional assemblies by mere addition of parts.

It is, therefore, an important object of the

2

present invention to provide apparatus for removing fluids from perforated rotating shells.

Another important object of the present invention is to provide means for effecting the removal of liquid from the surface perforations of a rotatable suction shell or drum of a paper making machine.

It is a further important object of the present invention to provide an improved roll assembly for a paper making machine including a suction drum and means for removing liquid from the surface perforations of the drum.

Still another important object of the present invention is to provide an improved apparatus for the removal of liquid from the surface perforations of a suction roll including means for introducing a fluid under pressure into the interior of the roll for escape through the surface perforations thereof in combination with means for receiving liquid thus removed from the roll.

Other and further important objects of this invention will be apparent from the disclosures in the specification and the accompanying drawings.

25 On the drawings:

Figure 1 is a fragmentary vertical cross section, partially diagrammatic in form, and with parts in elevation, of a suction press assembly for a paper making machine embodying the present invention; and

Figure 2 is a similar vertical cross section of a different type of press assembly also equipped with the shell de-watering construction of the present invention.

35 As shown on the drawings:

In Figure 1, reference numeral 10 refers generally to a suction press assembly including a pair of cooperating suction press drums or rolls 11 and 12 defining therebetween a suction nip 13 receiving a wet paper web 14 interposed between cooperating press felts 15 and 16.

The suction roll 11 includes a rotatably mounted, radially perforated cylinder or shell 17 journaled at its ends, as conventional in the art, for rotation about its longitudinal axis. A suction gland or box 18 is disposed within the cylinder 17 and extends along the interior of the cylinder 17 in a direction substantially parallel to its axis of rotation. The suction gland 18 carries radially outwardly extending packing strips 19 contacting the inner peripheral surface of the cylinder 17 at peripherally spaced points. The packing strips 19 cooperate to define therebetween a relatively broad, localized suction area A on the cylinder or shell 17.

The suction drum or roll 12 includes an outer rotatable, radially perforated, cylinder 20 substantially identical in construction with the cylinder 17 hereinbefore described. The suction gland or box 21 is mounted in the interior of the cylinder 20 and extends generally parallel to the axis of rotation of the cylinder 20. The suction gland 21 is provided with a plurality of packing strips extending radially outwardly therefrom into contact with the inner periphery of the drum 20. A pair of packing strips 22 and 23 is disposed in the lower portion of the drum 20 immediately above the restricted nip 13. The strips 22 (on the on-coming side of the nip) and 23 (on the off-running side of the nip) cooperate with the inner periphery of cylinder 20 to define a relatively narrow suction area B.

A third packing strip 24 cooperates with the strip 23 to define a suction area C which is of substantially greater width than the suction area B.

The suction gland 21 is provided with a relatively narrow, reduced opening 25 for connecting the suction area C with the interior of the gland, while the mouth 26 affording communication with the suction area B is unobstructed. A butterfly-type valve 27 is provided in the restricted opening 25 to adjust the size of the opening for varying the suction in the suction area C as compared with the suction in the suction area B. The butterfly valve 27 may be controlled by any suitable means (not shown), as by a control lever extending beyond one circular end face of the cylinder 20 to vary the relative suction values in the areas B and C.

An additional packing strip 28 is provided in spaced relation to the packing strip 24 to define an arcuate, relatively broad area 29 in the interior of the cylinder 20. The area 29 is peripherally spaced on the off-running side from the suction areas B and C so that, when the cylinder is rotated, the periphery of the cylinder first passes the suction area B, then the suction area C, then the area 29.

A fluid manifold or conduit 30 is connected to a suitable source of fluid (i. e. gas) under pressure, as for example, air, and communicates with the periphery of the drum 12 at that portion of the outer surface of the cylinder 20 overlying the chamber 29 (and adjacent the packing strip 28). Communication between the manifold 30 and the chamber 29 is provided by means of the manifold outlet mouth 31 provided with terminal packing strips 32 which extend into contact with or into closely spaced relation to the outer periphery of the cylinder 20 (thereby effecting a substantial seal therebetween). It will be seen in Figure 1 that fluid under pressure above the manifold 30 will be introduced into the chamber 29 through the radial perforations 20a of the cylinder 20 and that the fluid under pressure so introduced into chamber 29 will be free to escape from the chamber through additional perforations 20a not aligned with the inlet mouth 31 (and at an exposed portion of the shell 12 not covered by the manifold 30 or the felt 16).

Fluid under pressure escaping through the perforations 20a will carry with it any water which might be lodged in these perforations. A catch-all trough or shield 33 is disposed adjacent the cylinder 20 to overlie that portion of the cylinder adjacent the chamber 29 to receive water and air forced from the cylinder by the fluid under pressure. The shield 33 is provided with a lower horizontal leg 34 which extends into closely

spaced relation to the periphery of the cylinder 20 with an upturned terminal lip 35 preventing the escape of liquid from the trough while permitting the escape of excessive fluid pressure therefrom. A drain from the trough 33 is provided by a drain line 36 in the lower portion thereof.

As shown in Figure 1, the wet paper web 14, carried by press felt 15, is lapped about that portion or roll 11 ahead of the nip 13, the web and felt overlying the suction area A of the roll 11. The other press felt 16 is guided into contact with the web 14 while the web is supported by roll 11 and immediately ahead of the nip 13 so that the web 14 itself is not contacted by the roll 12. Water from the web will be drawn into suction box 18 of roll 11 due to the contact of the web 14 and the press felt 15 with the suction area A. Upon passing through the nip 13, the relatively high suction of the suction area B will serve to further de-water the moist web 14. However, a portion of the water removed from the web 14 and the felts 15 and 16 will remain in the radial perforations 20a of the cylinder 20. The relatively low suction of suction area C, as determined by the setting of the butterfly valve 27, will retain this water within the perforations 20a to prevent a re-wetting of the web as it leaves the nip.

The present invention efficiently removes all water from the shell holes or perforations by forcing air under pressure into the chamber 29 and then allowing this fluid to escape through the perforations into the interior of the catch-all shield or baffle 33. In this manner, effective removal of water from the perforations 20a is insured despite the speed of travel of the web 14.

It will be noted that the air chamber 29 is created by merely adding the single packing 28 to the suction roll 12 and by merely closing the ends of the chamber with end deckle plates or extensions of plates for the chambers B and C.

In Figure 2, a modification of the apparatus of Figure 1 is shown as employed in a press section equipped with a bottom suction roll 12 and a plain top roll 37. However, the shell de-watering construction is essentially the same as shown in Figure 1 and identical reference numerals designate similar parts of the apparatus. The operation of the shell de-watering device of Figure 2, is identical with the operation of the device of Figure 1 as will be readily appreciated by those skilled in the art.

It will, of course, be understood that various details of construction may be varied through a wide range without departing from the principles of this invention and it is, therefore, not the purpose to limit the patent granted hereon otherwise than necessitated by the scope of the appended claims.

60 We claim as our invention:

1. In a paper machine, a first press roll, a second press roll defining a press nip therewith, a felt trained through said press nip, means conveying the felt away from the first press roll surface at the off-running side of the press nip providing an exposed portion of the first press roll surface at the off-running side, said first press roll having a perforate rotating roll shell, a stationary suction gland mounted within said roll shell, first sealing means on said gland cooperating with said shell to define a suction area in the first press roll at said press nip, second sealing means on said gland defining a fluid pressure chamber between the gland and the shell extending from adjacent the suction area to a point

angularly displaced from the suction area on the off-running side of the exposed portion of said first press roll, said second sealing means including a packing strip at said point, a conduit mounted outside the roll shell adjacent said point and connected to a source of gas under pressure, third sealing means mounted on said conduit and cooperating with said shell to conduct a gas blast from said conduit through said shell adjacent said point into said fluid pressure chamber and then out through the exposed portion of said first press roll, and stationary fluid pressure receiving means positioned exteriorly of said shell opposite the exposed portion of said first press roll to receive fluid forced back through the shell.

2. In a paper machine having a first press roll, a second press roll defining a press nip therewith, a felt trained through said press nip, and means conveying the felt away from the first press roll surface at the off-running side of the press nip providing an exposed portion of the first press roll surface at the off-running side, the improvement in which said first press roll is provided with a perforate rotating roll shell, a stationary suction gland mounted within said roll shell, first sealing means on said gland cooperating with said shell to define a suction area in the first press roll at said press nip, a pair of packing strips on said gland defining a fluid pressure chamber between the gland and the shell extending from adjacent the suction area where one of the strips is positioned to a point where the other of the strips is positioned angularly displaced from the suction area on the off-running side of the exposed portion of said first press roll, a conduit mounted outside the roll shell adjacent said point and connected to a source of gas under pressure, second sealing means mounted on said conduit and cooperating with said shell to conduct a fluid blast from said conduit through said shell adjacent said point into said fluid pressure chamber and then out through the exposed portion of said first press roll, and stationary fluid pressure receiving means positioned exteriorly of said shell opposite the exposed portion of said first press roll to receive fluid forced back through the shell.

3. In a paper machine having a first press roll, a second press roll defining a press nip therewith, a felt trained through said press nip, means conveying the felt away from the first press roll surface at the off-running side of the press nip providing an exposed portion of the first press roll surface at the off-running side, the improvement in which said first press roll is provided with a perforate rotating roll shell, a stationary suction gland mounted within said roll shell, first sealing means on said gland cooperating with said shell to define a first suction area in the first press roll at said press nip, second sealing means on said gland defining a second suction area immediately adjacent the first area, third sealing means on said gland defining a fluid pressure chamber between the gland and the shell extending from adjacent the second suction area to a point angularly displaced from the second suction area on the off-running side of the exposed portion of said first press roll, said third sealing means including a packing strip at said point, a conduit mounted outside the roll shell adjacent said point and connected to a source of gas under pressure, third sealing means mounted on said conduit and cooperating with said shell to conduct a gas blast from said conduit through said shell adjacent said point into said fluid pressure chamber and then out through the exposed portion of said first press roll, and

stationary fluid pressure receiving means positioned exteriorly of said shell opposite the exposed portion of said first press roll to receive fluid forced back through the shell.

4. In a paper machine having a first press roll, a second press roll defining a press nip therewith, a felt trained through said press nip, and means conveying the felt away from the first press roll surface at the off-running side of the press nip, providing an exposed portion of the first press roll surface at the off-running side, the improvement in which said first press roll is provided with a perforate rotating shell, a stationary suction gland mounted within said roll shell, a first packing strip on the gland at the on-coming side of the press nip, a second packing strip on the gland at the off-running side of the press nip and cooperating with the first strip and the shell to define a suction area in the first press roll at said press nip, a third packing strip on the gland at a point angularly displaced from the second packing strip on the off-running side of the exposed portion of said first press roll and cooperating with a baffle portion of said gland and the second packing strip to define a fluid pressure chamber between the gland and the shell, a conduit mounted outside the roll shell adjacent said point and connected to a source of gas under pressure, sealing means mounted on said conduit and cooperating with said shell to conduct a gas blast from said conduit through said shell adjacent said point into said fluid pressure chamber and then out through the exposed portion of said first press roll, and stationary fluid pressure receiving means positioned exteriorly of said shell opposite the exposed portion of said first press roll to receive fluid forced back through the shell.

5. In a paper machine having a first press roll, a second press roll defining a press nip therewith, a felt trained through said press nip, and means conveying the felt away from the first press roll surface at the off-running side of the press nip providing an exposed portion of the first press roll surface at the off-running side, the improvement in which said first press roll is provided with a perforate rotating shell, a stationary suction gland mounted within said roll shell, a first packing strip on the gland at the on-coming side of the press nip, a second packing strip on the gland at the off-running side of the press nip and cooperating with the first strip and the shell to define a first suction area in the first press roll at said press nip, a third packing strip on the gland angularly spaced from the second strip and cooperating therewith to define a second suction area immediately adjacent and at the off-running side of the first suction area, a fourth packing strip on the gland at a point angularly displaced from the third packing strip on the off-running side of the exposed portion of said first press roll and cooperating with a baffle portion of said gland and the third packing strip to define a fluid pressure chamber between the gland and the shell, a conduit mounted outside the roll shell adjacent said point and connected to a source of gas under pressure, sealing means mounted on said conduit and cooperating with said shell to conduct a gas blast from said conduit through said shell adjacent said point into said fluid pressure chamber and then out through the exposed portion of said first press roll, and stationary fluid pressure receiving means positioned exteriorly of said shell

opposite the exposed portion of said first press roll to receive fluid forced back through the shell.
